COMPUTING MACHINE

Ernest Beaumont, Canton, Ohio

Application June 14, 1937, Serial No. 148,103

1 Claim. (Cl. 235—145)

The invention relates to that general class of machines constructed to mechanically add or carry on other computing operations, and adapted to register the result of those computations by suitable means, and more particularly to machines of this class in which the mechanism is caused to operate to do the adding or other computing by the operation of an electric motor.

Machines of this class are usually provided with a plurality of number keys adapted to be selectively depressed, representing the amount to be added or subtracted as the case may be, these number keys being adapted to set certain stops which regulate the extent of movement of parts of the mechanism when an operation is thereafter performed by the subsequent depression of an addition or a subtraction touch bar to perform the adding or subtracting operation as desired.

The object of the present invention is to do away with the addition key or bar and the subtraction key or bar commonly provided upon machines of this class, which require an extra movement of the operator's hand after each item is set up in the machine by depression of the number keys, and to provide an individual control or operating key associated with each number key and so positioned that as the operator depresses any number key he may with the same movement of his finger depress the corresponding control or operating key which starts the motor and causes the mechanism to operate to do the adding or other computing desired.

Machines of this class are usually provided with a longitudinally movable trip bar or other means adapted to be moved by depressing the adding or subtracting key or bar, the movement of this trip bar or equivalent means actuating mechanism which closes the circuit to the motor.

The present invention contemplates the provision of a depressible frame having cam means for longitudinally moving the trip bar or similar means, the frame being adapted to be depressed by the depression of any one of the individual control or operating keys.

Another object of the invention is to provide a telescopically mounted key button or head upon the key stem of each of the number keys of the machine in order to facilitate the depressing of a number key and the corresponding control or operating key with a single movement of the operator's finger.

The above objects together with others, which will be apparent from the drawing and the following description, or which may be later re-

ferred to, may be attained by constructing the machine in the manner illustrated in the accompanying drawing, in which

Figure 1 is a plan view with parts broken away of the keyboard portion of an adding or computing machine showing the invention applied thereto;

Fig. 2, a side elevation with parts broken away of the portion of the machine shown in Fig. 1;

Fig. 3, a detail sectional view taken as on the line 3—3, Fig. 2; and

Fig. 4, an enlarged detail section through one of the telescoping number key buttons.

Similar numerals refer to similar parts throughout the drawing.

The invention is applicable to various forms of adding and computing machines but for the purpose of illustration it is shown in the drawing as applied to the well known Allen-Wales adding machine.

The machine is illustrated only in part, it being considered sufficient for a description and illustration of the invention to show only the portion of the machine illustrated, the setting up mechanism registering or recording mechanism, computing mechanism and operating motor, which may be of any suitable form or arrangement, not being illustrated.

A portion of the casing of the machine is illustrated at 10 and the usual keyboard carried in the upper forward portion of the casing is indicated at 11. The usual number keys are provided with stems 12 slidably located through the keyboard 11 and surmounted by suitably inscribed buttons 13 as in usual practice, the latter being as usual numbered from 1 to 9 and arranged in any desired keyboard plan, eight banks of number keys being shown in Fig. 1.

The key stems 12 are adapted to slide through the usual apertures in the keyboard 11 in order to set certain stops (not shown) which regulate the extent of movement of certain parts (not shown) when an operation of the machine is thereafter performed, all as in usual and well known practice.

As shown in Fig. 4, each key button 13 may be telescopically mounted upon the corresponding key stem 12. This may be accomplished in any usual or well known manner, preferably by forming the button or head 13 hollow, as shown, and slidably mounted over a cup 13a, fixed upon the upper end of the key stem 12, a coil spring, or equivalent resilient means, being located within the cup and hollow button, whereby each number key has the usual setting up movement when

depressed to the position shown at A by the fifth key 13 from the left in Fig. 2, and then is capable of a further movement by further pressure upon the telescoping head which causes compression of the coil spring within the hollow key head and telescoping of the hollow key button 13 over the cup 13a.

It is usual practice to provide a longitudinally movable displaceable shift member 14, or other movable means, operatively connected to any suitable mechanism for closing the circuit to an electric motor which operates the machine, this shift member being arranged to be shifted longitudinally by the depression of a touch bar 15 located upon one side of the machine and arranged to be depressed after each item is set up upon the number keys.

Such machines require an extra movement of the operator's hand in order to operate the adding or subtraction touch bar after each item is set up on the number keys. In order to do away with this extra movement of the operator's hand as each item is set up in the machine, the present invention contemplates the provision of means associated with each number key for operating the displaceable shift member 14 or equivalent mechanism.

As shown in the drawing, an individual control key is associated with each number key and comprises a key stem 15 slidably located through the keyboard 11 and surmounted by an arcuate button or head 16 located below the button 13 of the corresponding number key and preferably substantially at the level to which said number key may be depressed, without telescoping of the button thereof, as indicated at A in Fig. 2, whereby it will be seen that when the operator depresses any number key, as the same reaches the setting up position shown at A, the finger may contact the head or button 16 of the corresponding control key which may thus be depressed in the same movement or operation of the finger, the telescoping head of the number key permitting the same to be pushed down further with the control key, without further moving the key stem of the number key.

Each of the key stems 15 may be slidably mounted through a suitable aperture 17 in a plate 18 located at a point spaced below the keyboard 11, a shoulder 18 being provided upon the key stem and adapted to be normally urged into contact with the underside of the plate 18 as by a pull spring 20 connected to each key stem and to the keyboard 11 or other stationary portion of the machine.

For the purpose of transmitting movement from the adding keys to the displaceable shift member 14 or equivalent mechanism, a vertically movable frame may be provided, this frame including a plurality of longitudinal bars 21 corresponding in number and position to the banks of keys.

In order to provide for uniform vertical move-

ment of this frame regardless of the portion thereof which may be depressed, a depending post 22 may be fixed to each corner portion of the frame, each post having a sliding fit within a tube 23 supported upon the bottom of the casing 10, a coil spring 24 being located around each tube and post and interposed between the vertically movable frame and said bottom wall of the casing.

Each of the key stems 15 has spaced shoulders 25 engaging over the upper edges of the corresponding bar 21 of the movable frame whereby when any one of the adding keys is depressed, the frame comprising the bars 21 will be moved downward.

The displaceable shift member 14 may be provided with one or more lugs 27 and the vertically movable frame 21 is provided with a similar number of ears 28, each having a cam surface 29 cooperating with one of the lugs 27 whereby downward movement of the frame 21, caused by depressing of any one of the control or adding keys, will cause a longitudinal movement of the shift member sufficient to operate the usual circuit closing means for the motor, whereby the motor will operate the machine in usual and well known manner.

In operating the machine each item is set up by depressing the desired number keys as in usual practice and upon the depression of the last number key of each item the operator may place his finger onto the corresponding control key so as to depress said last named key in order to operate the usual registering or recording mechanism of the machine in well known manner.

It will thus be seen that the setting up of an item and operation of the machine to register or record the item is more easily and quickly accomplished, the operator of the machine being able to operate the same to register or record each item without having to make an extra movement of his hand to the side of the machine.

I claim:

In a computing machine, a group of number keys each having a setting up movement and a further movement, a control key located at one side of each number key entirely independent of the number key and having an operating movement, the setting up movement of each number key bringing the same to a position substantially flush with the normal position of the corresponding control key and the further movement of each number key bringing the same to a position substantially flush with the operated movement of the corresponding control key, a longitudinally displaceable shift member normally at rest and having a projection thereon, and a vertically movable frame adapted to be depressed by the operation of any one of the control keys and having a cam cooperating with said projection for moving the displaceable shift member upon operation of one of the control keys.

ERNEST BEAUMONT.
